Des. 204,925
Patented May 24, 1966

204,925

BICYCLE FRAME

Joseph A. Silbereis and Donald A. Wolf, Dayton, Ohio,
assignors to The Huffman Manufacturing Company,
Miamisburg, Ohio, a corporation of Ohio

Filed Oct. 13, 1965, Ser. No. 87,448

Term of patent 14 years

(Cl. D90—8)

FIG-2

FIG-3

FIG-4

FIG-5

FIG-6

FIG. 1 is a front perspective of the bicycle frame showing our new design;

FIG. 2 is a side elevation;

FIG. 3 is a front elevation;

FIG. 4 is a top plan view thereof;

FIG. 5 is a side elevation view of a modified form; and

FIG. 6 is a view taken along the line 6-6 of FIG. 5.

The portions of a bicycle shown in broken lines in FIG. 1 are included for illustrative purposes only.

We claim:

The ornamental design for a bicycle frame, as shown and described.
